Primary Examiner — Jack Reickel*Assistant Examiner* — Sydney M Evans(74) *Attorney, Agent, or Firm* — KELLY & KELLEY, PLLC(57) **CLAIM**

The ornamental design for a pull latch as shown and described.

DESCRIPTION

FIG. 1 is a perspective view of a pull latch embodying my new design;

FIG. 2 is a top view thereof;

FIG. 3 is a front view thereof;

FIG. 4 is a side view thereof; and,

FIG. 5 is an opposite side view thereof.

The broken line showing is included for the purpose of illustrating environmental structure and forms no part of the claimed design.

1 Claim, 4 Drawing Sheets(56)
